UNITED STATES PATENT OFFICE

LINNIE G. NORDSTROM, OF GALVA, ILLINOIS, ASSIGNOR OF ONE-THIRD TO EDWIN L. STEPHENSON, OF GALVA, ILLINOIS

PUMP JACK

Application filed August 8, 1929. Serial No. 384,274.

This invention relates to pump jacks designed for actuating cylinder pumps at any angle, the jack being so constructed as to drive its pitman either upwardly, downwardly, horizontally, or at any intermediate angle found necessary.

Another object is to provide a jack the members of which are so assembled as to adapt them for use in different positions to compensate for lost motion, and to actuate the pump rod properly whether or not it is mounted in a guide and whether or not the parts are accurately adjusted.

A further object is to provide a jack that is not only useful for the purposes stated but can also be employed as a rigging for different kinds of wood sawing apparatus, this being due to the fact that the jack will adapt itself to the path of movement of the saw and allow it to work properly along the line of cut.

A still further object is to provide a jack utilizing a thrust equalizing means whereby motion is properly transmitted from separate rotating elements to a reciprocating element.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings.

Figure 1 is a front elevation of the jack connected to a rod.

Figure 2 is an enlarged vertical longitudinal section through the gear housing of the jack.

Figure 3 is an enlarged section on line 3—3, Figure 1.

Figure 4 is an enlarged section on line 4—4, Figure 1.

Figure 5 is an enlarged section on line 5—5, Figure 1.

Figure 6 is an end elevation showing the jack arranged for driving horizontally.

Figure 7 is an elevation of the removable cover plate of the gear housing.

Figure 8 is a top plan view of one of the housing pedestals.

Figure 9 is an elevation showing one side of a crank arm.

Figure 10 is an elevation showing the other side of the crank arm.

Figure 11 is a section on line 11—11, Figure 10.

Figure 12 is a view partly in section and partly in front elevation of the lower portion of one of the pitmen.

Figure 13 is a section on line 13—13, Figure 12.

Figure 14 is a section on line 14—14, Figure 1.

Figure 15 is a section on line 15—15, Figure 1.

Figure 16 is a view similar to Figure 14 but showing the parts differently arranged relative to each other for equalizing thrust from the two pitmen to the transmission rod.

Referring to the figures by characters of reference, 1 designates a housing that can be formed with a central partition 2 extending transversely thereof. This housing may be cast with an open face, said face being adapted to be closed by a cover plate or head 3. This plate can be reinforced by transverse ribs 4 on the outer side thereof. Screw-threaded recesses 5 may be formed in the ribs for the purpose hereinafter explained.

The housing 1 has spaced bearing sleeves 6 extending perpendicularly from the closed side thereof and each sleeve has a bushing 7 in which is journaled a shaft 8. The sleeves 6 may be reinforced by integral webs 9 radiating therefrom and extending from the closed side of the housing.

Secured to that end of each shaft 8 located within the housing is a gear 9' and these gears mesh with smaller gears 10 secured to a longitudinal shaft 11 that is journaled in the ends of the housing 1 and also in the partition 2. Another or drive shaft 12 is journaled in partition 2 and in one end of the housing 1 and has a gear 13 located close to the partition

that constantly meshes with another gear 14 secured to the shaft 11. One end of shaft 12 projects from the housing and is provided with any suitable means for driving the same, this means, if desired, including pulleys 15.

To the outer ends of the shafts 8 are connected crank arms 16 each of which may be reinforced by a longitudinal rib 17 on one side thereof. Extending through the arm 10 and longitudinally of the rib is a series of apertures 18 and any one of the apertures of said series is adapted to receive a wrist pin 19 that can be in the form of a bolt.

The two gears 9' are adapted to be driven 15 in opposite directions simultaneously by the gears 10 when shaft 11 is rotated. The crank arms 16 are extended oppositely and are adapted to rotate at the same speed so that once during each rotation the crank arms will 20 be extended toward each other and aline while once during each rotation they will be extended away from each other and aline. They will also simultaneously reach positions where they will be momentarily parallel.

25 Each wrist pin 19 is extended through a block 20 located between straps 21 to which the block is secured by a single bolt 22 extending through the block and the strap. This bolt is disposed at right angles to the 30 wrist pin. The opening 23 provided for the wrist pin has been shown clearly in Figures 12 and 13.

The straps 21 are bolted to opposite faces of a pitman 24. These pitmen are substantially parallel and those end portions thereof remote from the crank arm are formed with longitudinal series of apertures 25.

Fastened to the inner side of each pitman is a bracket 26, these brackets being preferably held adjustably to the pitmen by bolts 27 that can be extended through any of the apertures 25. Thus it is possible to arrange the brackets at any desired distances from the crank arms. The brackets are extended toward each other and their free ends are reduced to provide tongues 28 adapted to lap. A pivot bolt 29 may be extended through thelapping tongues and also through the base 30 of a coupling 31. This base has 50 spaced ears 32 adapted to receive between them one end of the transmission rod 33, which can be a pump rod or the like, the said rod being held to the ears by a pivot bolt 34. If preferred, the brackets 26 can be connected by two bolts 35 extending through the end portions of the base 30 of the coupling 31 and through apertures provided therefor in the brackets as indicated at 36. When these bolts 35 are employed the pivot bolt 29 is dispensed with. Thus the brackets 26 will 60 constitute an equalizing crosshead whereby it is possible for them to shift relative to each other should there be any undesirable relative movement of the pitmen 24.

65 When the pitmen are used for driving rod

33 upwardly and downwardly it is preferred to mount the housing 1 on pedestals 37 that extend transversely beneath the housing and are detachably held thereto by bolts as shown in Figure 1. When, however, the pitmen are 70 to be operated horizontally, the pedestals 37 can be arranged beneath the plate 3 and molded to the ribs 4, the screws employed being extended into the threaded socket 5 as shown in Figure 6.

75 When the apparatus is in either of these positions, actuation of shaft 12 will result in the transmission of motion to shaft 11 so that spring arms 16 will be actuated as already explained, thereby causing the pitmen 24 to reciprocate and oscillate. The oscillation of the pitmen is relative to each other due to the fact that the crank arms rotate in opposite directions respectively. This relative oscillation of the pitmen during their reciprocation is permitted because of the pivotal connection between the brackets 26 and bolts 29 or because of the equalizing connection between the brackets provided by the use of the bolts 35. This equalizing connection is employed usually when the rod 33 is mounted in a guide already provided therefor and the jack is applied to the rod for the purpose of actuating it.

80 Under the conditions just mentioned, it is almost impossible to mount the jack relative to the path of movement of the rod with sufficient accuracy to insure a positive thrust against the rod along the line of travel thereof. By providing the compensating cross-head formed of the brackets 26 connected by the coupling 31 and bolts 35, a limited relative movement of the parts is permitted in the cross-head so as to adapt the mechanism for use under the conditions stated and compensate for any lack of balance that might be present.

85 Obviously by providing the pivotal connection between the blocks 20 and the straps 21, it becomes possible to transmit motion 100 through the pitmen even though they may be disposed at angles between the horizontal and vertical positions.

90 What is claimed is:

1. A jack including a housing, crank arms supported outside thereof, means within the housing for rotating the crank arms simultaneously but in opposite directions respectively, means detachably connected to the housing for supporting it in either of two 115 positions, pitmen connected to and adapted to be actuated simultaneously by the respective crank arms, brackets adjustably connected to the respective pistons, a coupling movably connected to the brackets, and a rod 120 connected to and actuated by the coupling.

125 2. A jack including a housing, means detachably connected thereto for supporting the housing in either of two positions, crank arms rotatable relative to the housing, means 130

in the housing for simultaneously rotating the crank arms in opposite directions respectively, blocks carried by the crank arms and adjustably connected thereto, pitmen pivotally connected to the respective blocks, brackets adjustably connected to the respective pitmen, a rod, and a working connection between the rod and the brackets.

3. A jack including a housing, means detachably connected thereto for supporting the housing in either of two positions, crank arms rotatable relative to the housing, means in the housing for simultaneously rotating the crank arms in opposite directions respectively, blocks carried by the crank arms and adjustably connected thereto, pitmen pivotally connected to the respective blocks, brackets adjustably connected to the respective pitmen, a rod, and a working connection between the rod and the brackets, said connection including a coupling, pivotal connections between the coupling and the respective brackets, and a pivotal connection between the coupling and the rod, said brackets and pitmen being located at opposite sides of the rod and each pitman, with its bracket, being adapted to oscillate relative to the opposed pitman and bracket.

In testimony that I claim the foregoing as my own, I have hereunto affixed my signature.

LINNIE G. NORDSTROM.
